UNITED STATES PATENT OFFICE.

JOHN P. FANGEL, OF NEW YORK, N. Y.

LOCKING DEVICE FOR DESKS.

SPECIFICATION forming part of Letters Patent No. 638,226, dated December 5, 1899.

Application filed January 9, 1899, Serial No. 701,559. (No model.)

To all whom it may concern:

Be it known that I, JOHN P. FANGEL, a citizen of the United States, and a resident of New York city, county of New York, and State of New York, have invented certain new and useful Improvements in Locking Devices for Desks, of which the following is a specification, reference being had to the accompanying drawings, forming a part thereof, in which similar letters of reference indicate corresponding parts.

This invention relates to an improvement in locking devices for desks; and the object thereof is to provide a device of this character for the type of desks known as "roll-top" desks, in which all the drawers in the pedestals and the curtain may be locked automatically by the action of the central or master drawer.

Heretofore in roll-top desks it has been necessary to lock the curtain by means of a key, and when the curtain is so locked the drawers in the pedestals become locked automatically. Should it be desired to obtain access to any or all of the drawers in the pedestals of the desk, it is first necessary to unlock and raise the curtain before the drawers can be withdrawn.

This invention, which will be hereinafter fully described, and specifically set forth in the annexed claim, enables the user of the desk to lock the curtain alone, the drawers alone, or both together at will.

In the accompanying drawings, Figure 1 is a front elevation of a desk, all the drawers being removed and a portion of the back being broken away. Fig. 2 is a cross-section on the line 2 2 of Fig. 1, showing the curtain closed, but unlocked, and the lower part of the desk broken away. Fig. 3 is a cross-section on the line 2 2 of Fig. 1, showing the curtain closed and locked, the lower part of the desk being broken away; and Fig. 4 is a plan view of the locking devices, the top and front of the desk being partly broken away.

In the application of my invention I employ a vertically-slidable rod 1, preferably constructed of metal and rectangular in cross-section. This rod is adapted to slide through a suitable guide 2, fixed by means of screws or otherwise to the back 3 of the desk. The lower end 5 of said rod projects through a

suitable aperture in the rear portion of the desk-table 6. The upper end 7 of the rod 1 is bifurcated and in this bifurcation a rocking lever 8 is pivoted. This rocking lever 8 is fulcrumed to a standard 9, fixed to the under side of the top 10 of the roll-top portion of the desk. The forward end 11 of the rocking lever 8 has a head slightly enlarged and adapted to be moved away from and into contact with the under side of the top 10 by the action of the rod 1. A cleat 12, fixed to the forward edge of the top 10 upon its under side, is adapted to prevent the withdrawal of the rear bar 13 of the curtain 15 from its place.

The curtain 15 is adapted to slide in suitable ways 16, as in the ordinary roll-top desk.

A slot 17 in the rod 1 at a point near its upper end is adapted to receive a guide-screw 18.

Below the table 6 is mounted a vertically-slidable angle-iron 19, said angle-iron being provided with a slot 20 and guide-screw 21. The lower end of this iron projects through a suitable aperture in the lower table 22. The upper end of the angle-iron has an arm 23, projected at right angles therefrom, the upper face of this arm being in contact with the lower end of the rod 1. The outer underside 80 of this arm is beveled, as at 25.

A master-drawer 26 is adapted to slide in and out upon the lower table 22, and its rear wall is adapted for contact with the beveled edge 25 of the arm 23, so that when the drawer is pushed inwardly the angle-iron 19 will be elevated, which in turn will raise the rod 1 and throw the head 11 of the lever 8 into locked position behind the bars 13 of the curtain 15, as shown in Fig. 3.

Fixed to the under side of the table 6, and preferably extending the full length across the desk, is the block 27. This block 27 is provided with a recess 28, adapted to receive the bolt of an ordinary lock fixed in the front wall of the master-drawer and to retain it in position. The rear side of the block 27 is provided with a recess 29, also adapted to receive the bolt of the lock when the drawer is pushed away in to lock the curtain.

The pedestals are each provided with a combination-post 30, pivoted to the rocking arm 31, which is in turn pivoted to the locking-bar 32. The combination-posts are mounted

in the usual manner, vertically slideable in suitable guides, and the arm 31 rocks on the screw-pivots 33, secured to the back of the desk. The locking-bar 32 is provided with an arm 35, projected through a suitable slot 36 in the inner walls of the pedestals. The arms 36 are each provided with a spur 37, the under side of which is beveled and adapted to be raised when the master-drawer 26 is pushed inwardly and its rear wall comes in contact with the beveled side of said spurs. In the operation of the device, with the master-drawer 26 in the position shown in Fig. 2, the bar 1 drops of its own weight into the position shown, the curtain being unlocked. The rear wall of the drawer 26 being out of contact with the spurs 37, the locking-bars 32 fall of their own weight and raise the combination-post 30, so that the hooks are disengaged from the drawers in the pedestals and the whole desk is unlocked. To lock the desk, the curtain is drawn down, as shown in Fig. 3, and the master-drawer 26 pushed inwardly as far as it can go. The rear wall of the drawer will engage the beveled edge of the angle-iron 19 and raise it, thereby forcing the rod 1 upwardly and the head 11, with the rocking lever 8, downwardly behind the cross-bar 13 of the curtain. The curtain is thus effectually locked and cannot be raised until the master-drawer is pulled outwardly from its closed position. The same action of pushing the master-drawer inwardly elevates the locking-bars 32 32, and the hooks 35 on the combination-posts 30 30 engage the rear wall of the drawers 38 38.

It will be seen that no key-actuated lock is necessary on the curtain itself, and this is a material advantage over the types of desks now in use, for the reason that there is no aperture whatever in the table to collect dirt, &c., and no spring-plate to close said aperture and become useless by the breaking of the spring.

Obviously the bar 1 might be mounted at a point near one end of the desk and operated by the upper drawer of the set in one or both of the pedestals in desks which have no central drawer.

Having thus described my invention, what I claim as new, and desire to secure by Letters Patent, is—

In a desk, the combination of a sliding drawer, a vertically-slidable rod mounted in the back of the desk, a beveled spur adapted for contact with the rear wall of the drawer and to lift said rod, a rocking lever pivoted to the upper end of said rod and fulcrumed to the top of the desk, a curtain slidably mounted in suitable channels at each side of the desk, the free end of said rocking lever being adapted for contact with the rear bar of the curtain, whereby it is held in locked position, substantially as described.

In testimony that I claim the foregoing as my invention I have signed my name, in presence of two witnesses, this 6th day of January, 1899.

J. P. FANGEL.
